COMPARTMENTED SERVING TRAY

William Henry Day, Brantford, Ontario, Canada, assignor
to W. R. Grace & Co., Duncan, S.C.

Filed Sept. 20, 1973, Ser. No. 399,202

Term of patent 14 years

Int Cl. D7—99

U.S. Cl. D7—38

FIG. 1

FIG. 2

FIG. 3

FIG. 4

FIG. 5

FIG. 6

FIG. 1 is a top perspective view of a compartmented serving tray showing my new design;

FIG. 2 is a top plan view thereof;

FIG. 3 is a sectional view along line 3-3 of FIG. 2;

FIG. 4 is a sectional view along line 4-4 of FIG. 2;

FIG. 5 is a bottom plan view thereof; and

FIG. 6 is a side elevation thereof.

I claim:

The ornamental design for a compartmented serving tray, substantially as shown.
